ATTORNEY

UNITED STATES PATENT OFFICE

HANS BURMEISTER, OF BERLIN, GERMANY, ASSIGNOR TO PYRENE-MINIMAX CORPORATION, A CORPORATION OF DELAWARE

APPARATUS FOR FEEDING POWDER TO A STREAM OF WATER

Application filed January 3, 1929, Serial No. 330,126, and in Germany May 11, 1928.

The present invention relates to fire fighting apparatus and more particularly to apparatus for adding chemicals to a stream of water. In practice it frequently occurs that the requirements of use are satisfied after only a part of the charge of powder has been exhausted and if the unused powder has been maintained in dry condition it can be saved for future use. This invention has for one of its objects to provide an improved apparatus so constructed and arranged that the powder is maintained in dry condition until it is actually added to the stream for use. Another object is to provide a positively acting means for adding the powder to the stream of water.

In the preferred embodiment the invention provides an apparatus in which the powder can be mechanically forced into the stream while the flow of the water into the powder container is effectively prevented.

The nature and objects of the invention will be better understood from a description of a particular illustrative embodiment for the purpose of which description reference should be had to the accompanying drawings forming a part hereof and in which—

Figure 1 is a central sectional view of an apparatus embodying the invention taken on the line 1—1 of Fig. 2, and

Figure 2 is a central sectional view taken on the line 2—2 of Fig. 1.

The apparatus shown for the purposes of illustrating the invention comprises a positively acting wing pump like arrangement whereby powder can be fed from a hopper into a stream of water to be used for fire fighting purposes.

As shown conventionally the illustrative apparatus comprises a casing 5 with a water inlet 6, a foam outlet 7 and a powder inlet 8 on which is arranged a hopper 9. Within the body of the casing an eccentrically mounted rotor 10, having radially movable wing pistons 11, is secured to the shaft 12 and arranged to feed powder from the hopper to a stream of water entering through the inlet 6. In the assembled structure the body of the rotor fits closely within the casing so that there is little if any leakage

of water around the ends of the rotor. The rotor or pump like member also fits closely against the casing wall between the discharge outlet 7 and the powder inlet 8 so that no water is carried in the expanding pump chamber to the powder receiving position. The dry powder is thus fed without being substantially wet and without wetting the powder in the hopper. The pistons 11 make a substantially water tight closure against the side and circumferential walls of the casing. Radial movement is imparted to the pistons 11 by means of cam grooves 17 which are engaged by rollers 18 on the pistons.

It will be understood that the structure conventionally illustrated makes provision for positively forcing powder from the hopper 9 into the stream of water and if the apparatus is used to produce foam as is contemplated the foam will be passed out through the discharge outlet 7.

The pressure of the water from the inlet 6 may be relied upon to rotate the rotor or if desired the rotor may be positively driven as by means of a motor connected to the shaft 12.

I claim—

1. Apparatus for producing fire foam by feeding dry foam-forming powder into a stream of water, comprising a casing, a rotatable member within said casing forming a plurality of chambers of varying capacity, an inlet arranged to admit said powder to said chambers while the latter are expanding, a second inlet to admit water to said chambers at a later stage while still expanding, and an outlet for the discharge of the mixed powder and water communicating with said chambers while they are still expanded, substantially as described.

2. Apparatus for producing fire foam by feeding dry foam-forming powder into a stream of water, comprising a casing, a positively acting rotatable pump-like member mounted eccentrically in said casing and having grooved pistons movable radially therein and operative to provide within the casing a series of expanding pump chambers, an inlet to admit dry powder to said expanding cham-

bers, and a second inlet thereafter to admit water to said chambers while they are still expanding, together with a discharge outlet for the combined powder and water, said outlet being out of direct communication with both of said inlets and communicating with said chambers while they are at a point where they are expanded, substantially as described.

In testimony whereof, I have signed my name to this specification this 13th day of December 1929.

HANS BURMEISTER.
